Samuel D. Tose of Albany N.Y.
Letters Patent No 263. Dated Feby 1850. Anti-dated Nov 17. 1849

The schedule referred to in these Letters Patent & making part of the same.

To all whom it may concern:

Be it known that I, Sam'l. D. Tose, in the City and County of Albany, State of New York, have invented or produced a new ornamental design for a Banking Stove and I do hereby declare that the accompanying drawings are a full and accurate representation of my said design.

Fig 1. being a perspective view. Fig. 2. a view of the front, on a larger scale. Fig. 3. a view of the side. The Figures 2 & 3 showing the detail of the ornaments, to save labor in drawing, but one half of the ornaments upon the plates represented in Fig 2. are delineated: the remaining portion being similar to and symmetrical with those represented. The figures are not easily described in words but are fully represented in the drawings.

What I claim as my invention and desire to secure by Letters Patent is the combination and arrangement of ornamental figures, forming respectively the front & side plates of my stove, as herein represented & described.

Witnesses.

James M. Adams
George W. Gardner

Sam'l. D. Tose.
